3 Claims. (Cl. 230—160)

1

The invention relates to collapsible pumps for inflating hollow inflatable articles such as pneumatic mattresses, boats, tents, balloons, toys and other large volume and low pressure inflatable articles.

Objects of the invention are to provide an improved collapsible pump capable of inflating hollow inflatable articles, especially articles of the large volume and low pressure type such, for example, as pneumatic mattresses, toys, or the like; to provide for effective pumping action of the pump by virtue of manually extending a bellows thereof axially to draw an inflating medium such, for example, as air into the same through one end of the pump and manually collapsing the bellows axially thereof to force the inflating medium out of the same at the other end of the pump and into the inflatable article; to provide for cooperation of the pump structure with the hand of the operator to effect the functions of a check valve at the intake end of the pump; to provide for ease and convenience of manipulation of the pump, either as an individual unit detachably and independently connected to the inflatable article, or as an integral unitary part of the inflatable article; to provide for extensive flexibility together with lateral stability of the pump; to provide for compactness, lightweight, durability and imperviousness of the pump; and to provide for simplicity of construction, convenience and low cost of manufacture, and for effectiveness of operation.

These and other objects and advantages of the invention will be apparent from the following description.

In the accompanying drawings which form a part of this specification,

Fig. 1 is a view showing a collapsible bellows pump held manually extended by the hands of the operator and detachably connected to a pneumatic mattress, and constructed in accordance with and embodying the invention, parts being broken away,

Fig. 2 is a longitudinal cross-sectional view in an enlarged scale showing only the bellows pump in the extended condition with its intake and exhaust ends open to the atmosphere,

Fig. 3 is a perspective view showing a modified bellows pump in the collapsed condition and constituting an integral unitary part of a pneumatic mattress, parts being broken away and in section, and

Fig. 4 is a section in an enlarged scale taken along line 4—4 of Fig. 3 showing the bellows pump in the partially extended condition hav-

2

ing a mechanical check valve at the exhaust end of the pump, parts being broken away.

In the illustrative embodiment of the invention shown in Figs. 1 and 2, the construction of a collapsible pump having a bellows-like or accordian-like pumping action, includes an extensible-compressible hollow or tubular body 10 of suitable shape such, for example, as circular in cross-section having, preferably, a plurality of 10 interconnected, closed, axially-expansible, substantially equal, annular flexible folds 11, 11 extending peripherally continuous about the body in substantially parallel relation one to the other and laterally inward relative to the longitudinal axis 12 of the body, which annular folds are disposed in series longitudinally of the body 10 and constitute its continuous annular sidewall having a generally corrugated configuration. The axially-expansible flexible folds 11, 11 are joined together in sealing relation one to the other at their outer peripheral margins or portions 13, 13, and have at their inner peripheral margins or portions 14, 14 continuous annular flexible restraining partitions 15, 15 which extend laterally of 20 and within the body 10 in sealing relation to the sidewall thereof. Each partition 15 restrains laterally outward expansion of a fold 11 at its inner margin 14 and has a central aperture 16 to permit the passage of air. The hollow body 10 has flexible, closed end walls 17 and 18, respectively, each having a central aperture 19, 20 for the passage of air.

The hollow body 10 having the plurality of axially-expansible annular folds 11, 11, the closed end walls 17, 18 and the partitions 15, 35 15 is made of thin, extensively flexible, substantially impervious material capable of withstanding repetitive folding and flexure and the internal fluid pressures normally encountered in 40 use of the pump, and capable of resisting effectively aging, abrasive wear and puncture. In the preferred construction, the hollow body 10 may be made of square-woven, straight-laid textile fabric of filamentary material such, for example, as cotton, linen, rayon, nylon, glass fibers or the like, which fabric has stretch-resisting characteristics and is made substantially impervious or air-tight by being coated thinly and continuously on at least one side and desirably on both sides 50 with an elastic composition of rubber, natural or synthetic, or other rubber-like or synthetic material having substantially similar chemical composition or physical properties to natural rubber and resistant to aging and abrasion. The thin rubberized textile fabric is extensively flexible

for facilitating the extensibility, collapsibility and easy handling of the pump.

For facilitating the axial extension and axial compression of the hollow body 10 by relative movement of the hands 50, 51 of the operator, a disc-like manipulating element 21 is secured as by adhesive attachment to the flexible end wall 17 in superimposed, face-to-face sealing relation therewith, preferably only at a zone 25 spaced substantially and laterally inward of the outer margin 13, and has a central aperture 22 in alignment with the aperture 19 in the end wall 17 so that both apertures constitute the air-intake opening of the pump. Alternatively, the manipulating element 21 may, if desired, be bonded and attached to the end wall 17 throughout its area to provide a relatively less flexible end wall 17 construction but one that is suitable for hand manipulation purposes.

The disc-like manipulating element 21 is of material relatively less flexible than the material of the hollow body 10 and can, if desired, be made of stiff material such, for example, as aluminum, wood or the like. However, in the preferred construction and arrangement shown in the drawings, a desirable stiffness and flexibility of the disc-like manipulating element 21 may be provided by making the element of one or more thicknesses of suitable rubberized textile fabric. This fabric construction of the manipulating element 21 advantageously facilitates the hand 51 of the operator flexing and grasping the element 21, as shown especially in Fig. 1 for effecting the extension and compression of the hollow body 10, and facilitates flexure of the manipulating element 21 including the end wall 17 so that they conform to and coact with the hand 51 of the operator to effect the functions of a check valve at the air-intake opening of the pump.

The flexible manipulating element 21 has an annular portion 24 of substantial lateral extent projecting outwardly away from the attachment zone 25 at the intake end wall 17 so that sufficient material of the annular projecting portion 24 can be flexed approximately to the curvature of the palm and fingers of the hand 51 of the operator to provide good holding power for manual manipulation of the bellows pump by the operator. The attachment zone 25 of the manipulating element 21 may be of relatively less lateral extent than that of the annular projecting portion 24 to provide an annular seating surface on the outer face of the element 21 about its margin at the aperture 22. This seating surface by virtue of flexure of the manipulating element 21 and end wall 17 as a unit is adapted to conform and seat in temporary sealing relation with the palm of the hand 51 during the compression stroke of the pump, and to move away from the palm of the hand 51 during the extension or intake stroke of the pump. Thus, the manipulating element 21 and end wall 17 together with the hand 51 function as a check valve to permit the entrance or intake of the air from the atmosphere into the hollow body 10, while preventing objectionable leakage of air at the intake end of the pump during its compression stroke.

The particular arrangement shown in Figs. 1 and 2 provides maximum volumetric capacity of the pump when all the folds 11, 11 and both end walls 17, 18 are fully flexed and axially extended during the intake stroke of the pump as a result of axial pull exerted on the annular projecting portion 24 of the disc-like element 21

by the operator's hand 51. A reduced yet good volumetric capacity of the pump results when the manipulating element 21 is combined with and attached to the end wall 17 throughout its entire area; since the hand 51 of the operator then grips both the adjacent wall of the adjacent fold 11 and the combined end wall 17 and manipulating element 21 for manipulating the pump and for coating with the combined end wall 17 and element 21 to effect a check valve function at the intake end of the pump.

The other end wall 18 at the exhaust end of the pump has a suitable connection fitting 26 desirably of molded rubber construction having a bore 27 therethrough aligned with the aperture 20 and having an attaching flange 28 at one end thereof adhesively attached to the end wall 18. This permits air to flow from within the pump during its compression stroke to a hollow inflatable article 29 such, for example, as a pneumatic mattress by means of a flexible conduit 30 such, for example, as a rubber hose detachably engaging the fitting 26 and a suitable check valve 31 of the mattress 29.

The fitting 26 may be of a size and configuration which permit slipping the body of the fitting between the index and third fingers, for example, of the hand 50 with the palm of the hand facing toward the end wall 18, as shown especially in Fig. 1, so that the hand 50 not only has a firm grip on the fitting but also backingly supports the end wall.

To inflate the mattress from its extended uninflated condition, the collapsible bellows pump 35 is detachably connected to the check valve 31 of the mattress by the rubber hose 30, and is held by the hands 50, 51 of the operator at the connection fitting 26 and the annular projecting portion 24 of the manipulating element 21, as shown to Fig. 1. The annular marginal portion of the manipulating element 21 extending continuously about the aperture 22 and constituting the annular seating surface of the element is positioned at the lower region of the palm of the operator's hand 51 and capable of flexing toward and away from the palm for temporary closing and opening of the air-intake opening 19, 22 of the pump.

The intake stroke is produced by separating movement of the hands in the direction longitudinally or axially of the pump, whereby the axially-expansile annular folds 11, 11 are flexed and expanded or extended axially, while the seating surface of the manipulating element 21 is flexed away from the palm of the hand 51 so that air flows through the apertures 19, 22 into the interior of the extended hollow body 10. The compression stroke of the pump is produced by axial movement of the hands 50, 51 toward one another which movement results in flexure of the end wall 17 and the element 21 such that the seating surface of the element at the aperture 22 seats conformingly against the lower region of the palm of the hand 51 in temporary sealing relation. This closes the air-intake opening in the intake end wall 17 of the hollow body 10 and makes feasible compressing the air within the hollow body and compelling the compressed air to flow into the pneumatic mattress 29.

The check valve 31 of the mattress opens during the compression stroke of the pump and closes during the intake stroke.

Although the pump may be operated with the respective folds 11, 11 maintained substantially in axial alignment relative to one another and

to the longitudinal axis 12 of the body 10 as shown in Fig. 1, during the intake and compression strokes by moving the hands 50, 51 along a straight path coinciding with the longitudinal axis 12 of the hollow body 10, good results are obtained by having the folds 11, 11 and restraining partitions 15, 15 shifted laterally relative to one another and to one side of the longitudinal axis 12 of the hollow body 10 through movement of the hand 51 along a straight path inclined or tilted relative to the longitudinal axis 12.

The manipulating element 21 at a large part of its seating surface about the aperture 22 tends to remain loosely against the palm of the hand 51 due to the lateral shifting of the material of the folds 11, 11 and the end wall 17 at the opposite side of the body 10, when the hand 51 moves along the tilted path away from the hand 50 to extend the bellows, and thus permits the intake of air during the intake stroke of the pump. During movement of the hand 51 toward the hand 50 along the tilted path for producing the compression stroke, the laterally shifted disposition of the folds 11, 11 makes feasible a relatively quicker and more effective seal of the element 21 against the hand 51. Also, during the compression stroke, whether the folds 11, 11 be in the axially aligned or the axially shifted disposition, the pressure of air within the body 10 not only bulges the walls of the folds outwardly and axially for increased capacity, but advantageously exerts pressure axially against the intake end wall 17 at the seating surface of the manipulating element 21 to facilitate maintenance of the temporary seal of the manipulating element 21 against the palm of the hand 51. Outward unfolding of the folds 11, 11 is prevented by the restraint thereto provided by the partitions 15, 15 which at the same time provide for lateral stability of the pump in its extended condition.

The pump may be manufactured commercially using the rubberized textile fabric and by joining together in series two or more walled inflatable pockets. Each inflatable pocket may, if desired, be made as an individual unit formed of two pre-cut, apertured sheets of the rubberized textile fabric having the desired form such, for example, as circular, and secured adhesively together at their outer marginal portions 13, 13 in sealing relation one to the other throughout the peripheral extent or outer circumference of the sheets. Each united pair of outer marginal portions 13, 13 constitutes a reinforcing protective rib 32 extending laterally outward and circumferentially about the hollow body 10 to reinforce the folds 11, 11 at their region of joinder and to protect the hollow body 10 against accidental damage and puncture. The reinforcing protective ribs 32, 32 by virtue of their stiffening action, facilitate guiding the folds 11, 11 in the desired path of movement during the intake and compression strokes of the pump.

A plurality of the walled inflatable pockets are assembled with adjacent walls of adjacent inflatable pockets united and bonded together in sealing relation about the inner marginal portions at the apertures 16, the annular zone of attachment of adjacent walls being of substantial lateral extent to provide the annular apertured restraining partition 15 or common wall between adjacent inflatable pockets. The annular reinforcing ribs 32, 32 and the annular restraining partitions 15, 15, by virtue of their double thickness and increased stiffness, coact

with adjacent parts of the hollow body 10 to provide lateral stability of the body during the intake and compression strokes of the pump.

Subsequent to assembling the walled inflatable pockets constituting the hollow body 10, the flexible manipulating element 21 may be adhered to the intake end wall 17 and the fitting 26 may be secured to the exhaust end wall 18 in the manner described hereinabove.

10 The modified construction 34 shown in Figs. 3 and 4 differs from that shown in Figs. 1 and 2 in respect of the collapsible bellows pump 34 being of substantially square form in section rather than circular, being permanently attached directly to a pneumatic mattress 35, and having a suitable mechanical check valve 36 attached to the exhaust end wall 37 of the pump 34 and to the distensible wall 38 of the mattress 35.

15 The check valve 36, desirably of molded rubber construction, has a stepped bore 36a therethrough in alignment with the aperture 20 in the end wall 37 and with an aperture 39 in the wall 38 of the mattress 35 which may have one or more divider strips 40 for providing one or 20 more intercommunicating compartments 41 of the mattress. The stepped bore 36a construction provides a chamber 42 terminating at its upper end in a seating surface 43 and having across its lower end an apertured support element 44 whereby a ball valve element 45 is retained and floatingly supported in the chamber 42 so as to move axially to the seating shoulder 43 to effect a seal as shown by broken lines in Fig. 4, and move axially from the seating shoulder 43 to break the seal as shown by full lines in Fig. 4. The arrangement facilitates inflating the mattress while preventing the escape of air under pressure within the mattress through the pump 34. For deflating the mattress, a suitable exhaust valve fitting 46 may be suitable attached, for example, to the wall 38 at any desired position thereon.

25 The collapsible bellows pump 34 is operated in the manner described hereinabove for the pump 10 except that the check valve 36 is grasped by one hand of the operator with the palm and fingers facing and bracing the exhaust end wall 37. When the hollow body or bellows of the pump 34 is extended and compressed to effect a 30 pumping action, the mattress 35 is readily inflated and a suitable flexible manipulating element 47 functions like the element 21 to provide the required temporary seal against the palm of the other hand and to permit the intake of atmospheric air into the pump.

35 The invention provides an improved collapsible bellows pump manually operable and of any desired shape, although only the circular and substantially square shapes are shown and described. The pump can be utilized as an independent unit detachably connected to a hollow inflatable article, or can be permanently attached to the inflatable article. By virtue of the lateral restraint to outward unfolding of the folds 40 provided by the interior partitions together with the functioning of the reinforcing outer ribs at the joinder of adjacent folds, the pump has lateral stability during its intake and compression strokes. The invention advantageously utilizes a hand of the operator in cooperation with the flexible intake end wall of the pump to serve as a check valve at the intake end. The construction also provides a light-weight, compact, low-cost pump having minimum number of parts and 45 simplified, durable construction facilitating

convenience of manufacture and effectiveness of operation.

Variations may be made without departing from the scope of the invention as it is defined in the following claims.

I claim:

1. A manually operable extensible and collapsible pneumatic inflating pump comprising an axially collapsible and extensible sidewall joined at each end to axially spaced end walls, said sidewall being formed of highly flexible air impervious material and being of generally corrugated configuration, said sidewall offering relatively slight resistance to extension thereof from its collapsed condition, one of said end walls being apertured and provided with means for connection to the article to be inflated, the other of said end walls having an aperture therethrough, said pump having a grip flange extending radially outward of said latter named aperture and formed of manually flexible material, said flexible end wall having about the margin of said aperture and along said grip flange an unobstructed hand-receiving surface for flexibly conforming to and sealing against the palm of the hand when the grip flange is grasped by the fingers and the pump is moved toward its collapsed position, said grip flange having less resistance to flexing than the resistance of said sidewall to extension from its collapsed position, so that said grip flange flexes when the fingers of the hand grasp said grip flange and exert force for extending the pump from its collapsed condition causing the palm of the operator's hand to separate from the wall about said aperture thereby opening the interior of the pump to atmosphere, and check valve means in said connecting means arranged to close automatically upon extension of said pump.

2. In a manually operable extensible and collapsible pneumatic inflating pump, an axially collapsible and extensible sidewall joined at each end to axially spaced end walls, said sidewall being formed of highly flexible air impervious material and being of generally corrugated configuration, said sidewall offering relatively slight resistance to extension thereof from its collapsed condition, one of said end walls being apertured and provided with means for connecting to the article to be inflated, the other of said end walls having an aperture therethrough, and having a radial extension axially spaced from the adjacent sidewall portion and forming a grip flange, said grip flange and end wall being formed of flexible material and providing about the margin of said latter named aperture and along said grip flange an unobstructed hand-receiving surface for flexibly conforming to and sealing against the palm of the hand when the grip flange is grasped by the fingers and the pump is moved toward its

collapsed position, said grip flange having less resistance to flexing than the resistance of said sidewall to extension from its collapsed position, so that said grip flange flexes when the fingers of the hand grasp said grip flange and exert force for extending the pump from its collapsed condition causing the palm of the operator's hand to separate from the wall about said aperture thereby opening the interior of the pump to atmosphere.

3. In a manually operable extensible and collapsible pneumatic inflating pump, an axially collapsible and extensible sidewall joined at each end to axially spaced end walls, said sidewall being formed of a plurality of centrally apertured discs of highly flexible air impervious material, adjacent discs being overlapped and joined alternately at their inner and outer margins with the overlapped joint at the inner margins being of substantially greater radial extent than that at their outer margins, said sidewall offering relatively slight resistance to extension thereof from its collapsed condition, one of said end walls being apertured and provided with means for connecting to the article to be inflated, the other of said end walls having an aperture therethrough, and having a radial extension spaced from the sidewall and forming a grip flange, said grip flange and end wall being formed of flexible material and providing about the margin of said latter named aperture and along said grip flange an unobstructed hand-receiving surface for flexibly conforming to and sealing against the palm of the hand when the grip flange is grasped by the fingers and the pump is moved toward its collapsed position, said joints at the inner disc margins resisting radial outward buckling of the sidewall during collapse of the pump, said grip flange having less resistance to flexing than the resistance of said sidewall to extension from its collapsed position, so that said grip flange flexes when the fingers of the hand grasp said grip flange and exert force for extending the pump from its collapsed condition causing the palm of the operator's hand to separate from the wall about said aperture thereby opening the interior of the pump to atmosphere.
